Inventor:
Mordecai Bassan,
By his Attorney, Geo. W. Mait

UNITED STATES PATENT OFFICE.

MORDECAI BASSAN, OF BROOKLYN, NEW YORK.

MECHANICAL TOY.

Application filed May 31, 1923. Serial No. 642,511.

To all whom it may concern:

Be it known that I, MORDECAI BASSAN, a native of Palestine, having declared my intention of becoming a citizen of the United States, and being a resident of the borough of Brooklyn, county of Kings, city and State of New York, have invented certain new and useful Improvements in Mechanical Toys, of which the following is a specification sufficient to enable those skilled in the art to which the invention appertains to utilize the same.

My improvements relate to mechanical toys in which a bellows is used for the purpose of sound production through the medium of an air vibrating device in a manner well known in the art; the novelty in the present case consisting primarily in utilizing the movable member of the bellows to effect the revolution of one or more figures or objects around an axis of rotation, substantially in the manner described.

To this end the invention consists in the specific construction, combination, and arrangement of parts claimed,—distinctive features being the mechanism employed for changing the reciprocatory motion of the movable member of the bellows into rotary motion for effecting the travel of the figure or figures around a prescribed circuit, and for imparting a jumping effect thereto enroute, all as hereinafter set forth.

In the accompanying drawings I exemplify a practical embodiment of the essential features of my invention in a sound producing rotative toy of the character designated although I do not restrict myself to the identical form of parts shown, since modifications in minor details of configuration and construction, and equivalent mechanical expedients, may be resorted to with like results, and without departing from the spirit and intent of my invention in this respect.

With this understanding,

Fig. 1, represents a top view of my new toy; and

Fig. 2, a view of the under side thereof;

Fig. 3, is a sectional elevation taken upon plane of line 3—3, Fig. 1;

Fig. 4, is an elevation, upon an enlarged

scale, showing more clearly the actuating parts;

Fig. 5, is a detail view illustrating the vaulting action of the figures,

A, is the rigid base plate, formed of any desired material and configuration, to the under side of which is affixed the stationary member b, of the bellows B, the movable member b', of which is pivotally attached, as at b², to the base A, and to said stationary member b, as indicated more particularly in Fig. 2, of the drawings. In either member of the bellows B, a reed r, or equivalent sound producing device is mounted, preferably one emitting a sound appropriate to a figure movably mounted on the upper side of the base plate A.

S, is a central spindle mounted in and extending through the base plate A. On the lower portion of this spindle is rigidly secured a cog wheel s, of suitable diameter, which meshes with a crank pinion p, also mounted on the base A. A pitman p', connects this crank pinion p, with a bell-crank lever c, also fulcrumed on the base plate A, and articulately connected in turn, by means of the thrust rod c', with the movable member b', of the bellows B. This combination and arrangement of actuating mechanism will be seen and understood by reference more particularly to Fig. 2 of the drawings.

By the use of the crank pinion p, in connection with the larger gear s, I am enabled to impart a relatively slow, continuous motion to the spindle S, by the reciprocation of the movable member b', of the bellows B.

One or more radial arms s^x, are pivotally mounted on the upper portion of the spindle S, in a manner shown more particularly in Fig. 4, of the drawings, each arm s^x, being formed with a stop shoulder s', which, by contacting with the spindle S, as shown in said Fig. 4, limits the downward motion of said arm s^x.

A figure f, or representation thereof, is mounted on the outer extremity of the radial arm s^x, or each of them if a plurality of such arms are provided; and during the operation of the toy the figure, (or figures, as the case may be) will obviously tra-

verse a circular path concentric with the spindle S.

To render the toy more attractive and amusing in use, one or more obstacles or hurdles *h*, may be positioned in the path of the figure *f*, and between each obstacle thus positioned and the spindle S, a stationary cam *d*, may be interposed in the path of the radial arm or arms *s*, so as to 10 tilt the latter upward as it passes thereover, and thereby cause the figure to rise and clear the hurdle or other obstacle *h*.

By this means my device is rendered capable of interesting effects. Thus, a horse 15 or other hurdle race may be portrayed; or one animal chasing another, as for instance, a dog chasing a cat, in which case the sounding device *r*, actuated by the bellows B, may be made to simulate the bark of a dog, 20 and so on. In fact my new toy mechanism is susceptible of many variations in detail and effect.

A compressive spring *k*, may be interposed between the movable member *b'*, of 25 the bellows B, and the stationary member *b*, thereof to insure a prompt expansion of the bellows after compression by the fingers of the user.

It is to be understood that the heads or 30 other parts of the figures may be articulately or otherwise connected to the bodies thereof so as to vibrate during the operation of the device, if so desired.

What I claim as my invention and desire 35 to secure by Letters Patent is,

1. A mechanical toy of the character designated, comprising a base plate, a bellows positioned to the under side thereof, a sound producing device connected with said bellows 40 a spindle mounted on and extending through said base plate, and rotated by intermediate drive mechanism by motion derived from the movable member of the bellows, a radial arm on the upper portion 45 of the spindle, and a figure mounted on said arm, substantially in the manner and for the purpose set forth.

2. A mechanical toy of the character designated, comprising a base plate, a bellows 50 positioned to the under side thereof, a sound producing device actuated by said bellows, a spindle mounted on and extending through said base plate and rotated by intermediate drive mechanism by motion 55 derived from the movable member of the bellows, a radial arm pivotally connected to the upper portion of said spindle, a stationary cam on the upper side of said base plate interposed in the path of said radial arm, and a figure mounted on said 60 arm, substantially in the manner and for the purpose set forth.

3. A mechanical toy of the character designated, comprising a base plate, a bellows 65 positioned to the under side thereof,

a sound producing device actuated by said bellows, a spindle mounted on and extending through said base plate, and rotatable by intermediate drive mechanism by motion derived from the movable member of the 70 bellows, a plurality of radial arms attached to the upper portion of said spindle, and figures mounted on said radial arms, substantially in the manner and for the purpose described. 75

4. A mechanical toy of the character designated, comprising a base plate, a bellows positioned on the under side thereof, a sound-producing device actuated by said bellows, a spindle mounted on and extended by 80 intermediate drive mechanism by motion derived from the movable member of the bellows, a plurality of radial arms pivotally connected with the upper portion of 85 said spindle, stationary cams on the upper side of said base plate interposed in the path of said radial arms, and figures mounted on said radial arms, substantially in the manner and for the purpose set 90 forth. 95

5. A mechanical toy of the character designated, comprising a base plate, a bellows positioned on the under side thereof, a sound producing device actuated by said bellows, a spindle mounted on and extending through said base plate, a gear wheel secured to the lower end of said spindle, a crank pinion mounted on the under side 100 of said base plate and meshing with the gear wheel on the spindle, a pitman connecting said crank pinion with a bell crank, said bell crank fulcrumed on the under side of said base plate, a thrust rod pivotally connecting said bell crank with the movable member of said bellows, a radial arm on the upper portion of said spindle, and a figure mounted on said arm, substantially in the manner and for the purpose set forth. 105

6. A mechanical toy of the character designated, comprising a base plate, a bellows positioned to the under side thereof, a sound producing device actuated by said bellows, a spindle mounted on and extending through said base plate and rotated by 110 intermediate drive mechanism by motion derived from the movable member of the bellows, a radial arm pivotally connected to the upper portion of said spindle, a figure mounted on the outer end of said radial arm, an obstacle on the upper side of said base plate interposed in the path of said figure, and a stationary cam on the upper side of said base plate interposed in the path of said radial arm, substantially in 115 the manner and for the purpose described. 120

7. A mechanical toy embodying a base plate, a bellows positioned on one side thereof, gear mechanism connected with and actuated by the movable member of said 125

5 bellows, radial arms operatively connected with the spindle of a member of the gear mechanism, figures mounted on said arms and oppositely-disposed cams on said base plate in the path of said arms.

8. A mechanical toy embodying a base plate, a bellows positioned on one side thereof, gear mechanism connected with and actuated by the movable member of said 10 bellows, radial arms operatively connected

with the spindle of a member of the gear mechanism, figures carried by said arms, cams on said base plate in the path of said arms, and hurdles on the base plate in the path of the said arms, the said cams being disposed between said hurdles and spindle. 15
